CLAMP FOR HEEL DOWELING MACHINES

Charles A. Davis, Saugus, Mass., assignor to W. J. Young
Machinery Co., Inc., Lynn, Mass.

Application January 2, 1958, Serial No. 706,826

3 Claims. (Cl. 12—123.3)

The present invention relates to a heel doweling machine and more particularly to a heel doweling machine adapted to drill holes and insert dowels therein, with the holes and dowels extending from the upper surface of the heel downwardly through the neck of the heel to a point above its bottom.

An object of the present invention is to provide a means, by which heels, and particularly plastic heels made of such materials as acetate and having a slender elongated neck may be substantially reinforced by the insertion of a metal rod within the heel, without the marring or drilling of the lower base of the heel to which lifts are normally nailed.

In the present day manufacture of ladies' shoes, there has been a substantial trend towards the utilization of plastic heels having very narrow necks or shanks which taper down to a bottom surface ordinarily having a diameter of no more than $\frac{1}{2}$ ". As plastics, unless reinforced, are quite apt to crack upon the application of excessive torques or other pressures, it has become customary in the trade to reinforce the plastic heels by drilling a dowel hole from the bottom surface upwardly through the narrow neck into the larger upper portion of the heel, after which a reinforcing dowel of metal or the like is inserted. In order to attach the lift, however, it is necessary to close off the hole in the lower surface of the heel to provide an area to which the lift may be attached by nailing. In the past the trade has resorted to the expensive and inconvenient technique of filling the lower end of the dowel hole with a wooden plug or the like to which nails may be secured. This has proved relatively unsatisfactory because it is not only an expensive procedure, but also because it does not really secure the lifts in a manner which is satisfactory.

The present invention is designed to overcome this difficulty by providing both a heel having a narrow neck or shank of improved design and also a device for satisfactorily processing these heels.

In the present invention, the heel having a narrow elongated shank is drilled from the upper surface which normally faces the sole of the shoe. This hole within which is positioned the reinforcing dowel, extends downwardly through the narrow neck portion of the heel to a point some distance above the lower surface of the heel thus providing a reinforced heel, while at the same time maintaining the smooth unbroken lower surface to which lifts may readily be attached by old conventional means.

In order to provide such a structure, however, great care must be taken in the drilling procedure and insertion of the dowel, for where narrow neck heels such as the ones under consideration are being processed, the tolerances which must be maintained when drilling from the upper ends of the heels, are considerably smaller than those when drilling from the lower end of the heel. Accordingly the present invention provides a means adapted to be used in conjunction with a heel doweling machine for assuring that the heels will be properly

2

located and secured for the drilling procedure. This clamping means is used in conjunction with a doweling machine such as disclosed in U.S. Letters Patent No. 1,986,458, issued January 1, 1935, to W. J. Young.

5 This clamping device is adapted to be used in conjunction with such a machine, and preferably a four station machine with the clamping member secured to the work carrier in such a manner as to be successively rotated into the drilling area, while at the same time maintaining heels inserted therein in selected positions for drilling.

10 It is also an object of the present invention to provide an improved clamping device adapted to secure a heel for drilling on a heel doweling machine with the lower surface of the heel faced downwardly in such a manner as to permit drilling of the heel along a vertical axis from the upper surface thereof. A further object of the present invention is to provide a clamp for securing heels, preferably of the plastic variety, in the manner as described, with the clamping means providing a 15 plurality of adjustable controls adapted to permit heels of various shapes and sizes to be readily substituted in the clamp.

20 These and other objects and advantages of the present invention will be more clearly understood when considered in connection with the accompanying drawings, in which:

Figure 1 is a side elevation of the clamp of the present invention as positioned on the work carrier.

Figure 2 is an end view of one element illustrated in Figure 1.

Figure 3 is a top plan view of a second element illustrated in Figure 1.

Figure 4 is a top plan view of a third element as illustrated in Figure 1, and

35 Figure 5 is a perspective view of a fourth element illustrated in Figure 1.

Figure 6 is a cross sectional elevation of a heel in part manufactured by the device of the present invention.

The clamping device of the present invention is 40 designed for use in conjunction with heel doweling machines such as is illustrated in U.S. Letters Patent No. 1,986,458, and in particular is designed for substitution of clamping members such as shown in Figures 8 and 9 of that reference. In this arrangement, the base 1 is 45 preferably a rectangular metal block, secured to the work carrier 2. This block 1 may be provided with a longitudinally extending channel 3, formed in its lower surface and adapted to fit over a corresponding shoulder on the carrier 2. A machine screw 4, passing upwardly through the carrier 2 into the base 1, secures it in selective position. An angle member 5 having legs 6 and 7 is secured to the rear wall 8 of the base 1 by a plurality of machine screws 9 and 10 which pass through the lower end of the leg 6 into the rear wall 8 of the base 1. 50 The leg 7 of this angle member 5 extends forwardly over and parallel to the upper surface 11 of the base 1. A flat template 12 is secured with its rear portion in face relation to the upper surface of the leg 7, by means of a machine screw 13 which passes downwardly through a slot 14 in the template 12 into the upper surface 55 of the leg 7, with the head of the machine screw 13 engaging the upper surface of the template 12 on either side of the slot 14. The template 12, best illustrated in Figure 4, is provided as indicated with the rearwardly extending slot 14 and a forwardly directed V-shaped recess 15 longitudinally aligned with the slot 14. This recess 15 is adapted to engage the upper rear portions of a ladies' heel when positioned in the clamp. The template 12 is adjustable by loosening the screw 13 to 60 permit its retraction to a more rearward position for the insertion of a large or different size heel.

Secured to the upper surface of the base 1, is a

support 17 which is slidably secured to the base by a plurality of machine screws 18 which project downwardly through slots 19 and 20 in the support 17 into the upper surface 11 of the base 1. The heads of the machine screw engage in slidable fashion the upper surface of the support 17 on either side of the slots 19 and 20. The support 17 is longitudinally slideable over the surface of the base 1, guided by the machine screws 18 and the slots 19 and 20 by the screw 21 which projects from the rear of the clamp through the leg 6 into the support 17. The screw 21 is provided with a knurled head 22 at one end, with its other end threaded into a recess in the support 17. The screw 21 is secured or journaled in the leg 6 by means of bearings 23, which permit its rotation and thereby permits longitudinal movement of the support 17. The forward end of this support is provided with a V-shaped recess 27 adapted to engage the lower end of a heel such as is illustrated by the lower end 28 of heel 29.

Also provided in this mechanism for securing the selected heel 29 in a particular position with a minimum of adjustment is the inverted U-shaped member 30. This member comprises a pair of arms 31 and 32 pivotally secured at their lower end as indicated at 33 to opposite sides of the base 1, with the cross member 34 secured at the other end extending over the top surface 11 of the base 1. This cross member 34 is adapted to engage the forward lower surface 37 of the heel 29. This cross member 34 is spring tensioned rearwardly against the stop 38 extending outwardly into contacting engagement with the arms 31 or 32 from the side wall of the base 1 by means of a spring 39 which is secured at one end to the pin 40 and at the other end to the pin 41. The pin 40 in turn, forms a portion of arm 32, while pin 41 is secured to the side of the base 1.

Thus it will be observed from the construction described, means are provided for securing a heel 29 in an upright position with the particular location of the heel being subject to a precise determination, so that the drilling of doweling holes from the upper surface 51 for the purpose of inserting dowels may be accurately assured.

As indicated in the cited patent, these clamping mechanisms form one of several clamping mechanisms, each adapted to be moved successively from one station to another, in which at one station a hole may be drilled and in the second a dowel may be inserted for reinforcing the heel. By the precise controls obtainable through adjustment of screws 21 and 13, and the constant positioning tension obtained by the member 30, a precise accuracy in the drilling of holes in successive heels may be obtained. Further there is little likelihood of inaccuracies in the drilling which might permit the drilled holes to pass through the wall of the heel at the slender neck portion. These results are obtainable in a manner which still permits the ready removal of the heel for the insertion of additional ones.

Referring now to Figure 6, a typical construction of heel is shown. In this arrangement a plastic heel 50 having an upper surface 51 and a lower surface 52 is formed with a slender neck or shank 53. A reinforcing rod 54 is inserted within an elongated hole 55 formed substantially vertically from the upper surface 51 downwardly to a point 56 which is spaced above the lower

surface 52 a sufficient distance to permit heel lifts to be secured to the heel.

Having now described my invention, I claim:

1. For use with a heel doweling machine having a vertically positioned drill, a clamping mechanism adapted to precisely locate a heel below said drill, comprising a template and support, each having a recess adapted to receive the rear of a heel, means adjustably securing said template and support for parallel movement with said recesses adapted to receive said heel and position it with the wider portion upward and the elongated neck vertically aligned, and means for removably securing said heel in said position, comprising a cross bar, an arm pivotally supporting said bar for movement toward and away from said recesses for engagement and disengagement, respectively, with said heel positioned therein, and means tensioning said bar toward said recesses, said means for adjustably securing said template and support comprising a base slidably supporting said support and a member 10 slidably supporting said template above said support, and means for securing said support and template in selected positions.
2. For use with a heel doweling machine having a vertically positioned drill, a clamping mechanism adapted to precisely locate a heel below said drill, comprising a template and support, each having a recess adapted to receive the rear of a heel, means adjustably securing said template and support for parallel movement with said recesses adapted to receive said heel and position it with the wider portion upward and the elongated neck vertically aligned, and means for removably securing said heel in said position, comprising a cross bar, an arm pivotally supporting said bar for movement toward and away from said recesses for engagement and disengagement, respectively, with said heel positioned therein, and means tensioning said bar toward said recesses, said means for adjustably securing said template and support comprising a base 15 slidably supporting said support and a member 20 slidably supporting said template above said support, and means for securing said support and template in selected positions.
- 25 3. For use with a heel doweling machine having a vertically positioned drill, a clamping mechanism adapted to precisely locate a heel below said drill, comprising a template and support, each having a recess adapted to receive the rear of a heel, means adjustably securing said template and support for parallel movement with said recesses adapted to receive said heel and position it with the wider portion upward and the elongated neck vertically aligned, and means for removably securing said heel in said position, comprising a cross bar, an arm pivotally supporting said bar for movement toward and away from said recesses for engagement and disengagement, respectively, with said heel positioned therein, and means tensioning said bar toward said recesses, wherein said means for adjustably securing said template and support comprises a base 30 slidably supporting said support, an angle member secured at one end to said base 35 and slidably supporting said template at the other end parallel to and on a level above said support, and means securing said support and template in selected positions.
- 35 4. For use with a heel doweling machine having a vertically positioned drill, a clamping mechanism adapted to precisely locate a heel below said drill, comprising a template and support, each having a recess adapted to receive the rear of a heel, means adjustably securing said template and support for parallel movement with said recesses adapted to receive said heel and position it with the wider portion upward and the elongated neck vertically aligned, and means for removably securing said heel in said position, comprising a cross bar, an arm pivotally supporting said bar for movement toward and away from said recesses for engagement and disengagement, respectively, with said heel positioned therein, and means tensioning said bar toward said recesses, 40 wherein said means for adjustably securing said template and support comprises a base slidably supporting said support, an angle member secured at one end to said base 45 and slidably supporting said template at the other end parallel to and on a level above said support, and means securing said support and template in selected positions.
- 45 5. For use with a heel doweling machine having a vertically positioned drill, a clamping mechanism adapted to precisely locate a heel below said drill, comprising a template and support, each having a recess adapted to receive the rear of a heel, means adjustably securing said template and support for parallel movement with said recesses adapted to receive said heel and position it with the wider portion upward and the elongated neck vertically aligned, and means for removably securing said heel in said position, comprising a cross bar, an arm pivotally supporting said bar for movement toward and away from said recesses for engagement and disengagement, respectively, with said heel positioned therein, and means tensioning said bar toward said recesses, 50 wherein said means for adjustably securing said template and support comprises a base slidably supporting said support, an angle member secured at one end to said base 55 and slidably supporting said template at the other end parallel to and on a level above said support, and means securing said support and template in selected positions.
- 55 6. For use with a heel doweling machine having a vertically positioned drill, a clamping mechanism adapted to precisely locate a heel below said drill, comprising a template and support, each having a recess adapted to receive the rear of a heel, means adjustably securing said template and support for parallel movement with said recesses adapted to receive said heel and position it with the wider portion upward and the elongated neck vertically aligned, and means for removably securing said heel in said position, comprising a cross bar, an arm pivotally supporting said bar for movement toward and away from said recesses for engagement and disengagement, respectively, with said heel positioned therein, and means tensioning said bar toward said recesses.
